US00D815070S

(12) **United States Design Patent** (10) **Patent No.:** **US D815,070 S**
(45) **Date of Patent:** **** Apr. 10, 2018**

(54) **ELECTRONIC DEVICE**

(71) Applicant: **Facebook, Inc.**, Menlo Park, CA (US)

(72) Inventors: **Baback Elmieh**, Palo Alto, CA (US); **Alexandre Jais**, Menlo Park, CA (US); **Rex Wenters Crossen**, Piedmont, CA (US); **Steve Sangik Lee**, San Francisco, CA (US); **Achille Biteau**, San Francisco, CA (US); **Victoria Slaker**, San Francisco, CA (US); **Clara Stefanov Wagner**, San Francisco, CA (US); **Zoltan Laszlo**, San Francisco, CA (US); **Arturo Meuniot**, San Francisco, CA (US)

(73) Assignee: **Facebook, Inc.**, Menlo Park, CA (US)

(***) Term: **15 Years**

(21) Appl. No.: **29/589,311**

(22) Filed: **Dec. 29, 2016**

(51) LOC (11) Cl. **14-01**

(52) U.S. Cl.

USPC **D14/225; D14/240**

(58) **Field of Classification Search**

USPC ... D14/227, 225, 358, 357, 204, 209.1, 211, D14/214, 215, 221, 140, 142, 240, 242, D14/241, 314, 348, 217, 168, 137, 194, D14/159, 349, 356, 496, 501, 299, 40; D16/202; D13/107; D9/423, 432; 361/752; D10/106.1; 381/380, 381, 386; 379/428.04, 420.01; 455/90.3, 575.1, 455/569.1

CPC H04R 1/02; H04R 1/28; H05K 5/00; G06F 1/16

(57) **CLAIM**

The ornamental design for an electronic device, as shown and described.

DESCRIPTION

FIG. 1 is a perspective view of an electronic device, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicted in the figures form no part of the claimed design.

1 Claim, 7 Drawing Sheets
